(57) **CLAIM**

The ornamental design for a protective case for gamepad, as shown and described.

DESCRIPTION

FIG. 1 is a perspective view of a protective case for gamepad showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the protective case for gamepad where a game pad is received in the protective case for gamepad and an upper cover is covered on the protective case for gamepad;

FIG. 10 is a perspective view of the protective case for gamepad where the game pad is received in the protective case for gamepad and card organizers of the upper cover is in an open position; and,

FIG. 11 is a perspective view of the protective case for gamepad where the gamepad is received in the protective case for gamepad and the upper cover is sleeved on the protective case for gamepad.

The broken lines in the drawings depict portions of the protective case for gamepad that form no part of the claim. The broken lines showing of a gamepad and upper cover, in FIGS. 9-11, illustrate environmental structure that form no part of the claimed design.

1 Claim, 11 Drawing Sheets
